WORK HOLDING MEANS FOR PRESSING MACHINES

Application filed September 18, 1929. Serial No. 392,796.

This invention relates to garment and laundry pressing machines and has for its object a particularly simple and efficient work or tail holding mechanism for holding the work on the lower pressing element or buck.

The invention consists in the novel features and in the combinations and constructions hereinafter set forth and claimed.

In describing this invention reference is had to the accompanying drawings in which like characters represent corresponding parts in all the views.

Fig. 1 is a fragmentary side elevation of a pressing machine showing the work or tail holder mechanism.

Fig. 2 is a front elevation of parts seen in Fig. 1.

Fig. 3 is a sectional view, partly diagrammatic, of the power means for actuating the work holder and the controls therefor.

Fig. 4 is a side elevation of a pressing machine on a reduced scale provided with my invention.

The invention is here shown as applied to a conventional type of pressing machine in which the cooperating pressing elements are respectively, a buck 1 and a head 2 movable toward and from the buck, the buck being mounted on the suitable bolster 3 which in turn is supported on a table or frame 4; and the head 2 being carried by a frame lever 5 pivoted between its ends at 6 to an upright 7 rising from the frame. In the machine here illustrated, the machine is actuated by motor means, and the motor means, as here shown, is a cylinder 8 having a piston 9 therein, the rod 10 of which is connected to the head 2 through suitable motion transmitting mechanism. This motion transmitting mechanism, in addition to the lever 5 includes links 11 and 12 pivoted together at 13 and pivoted at 14 and 15 respectively to the rear arm of the lever 5 and the pressing machine frame. The link 12 has a forwardly extending arm 16 which is pivoted at 17 to the end of the piston rod 10. The piston 9 is single acting and the press is opened, when the pressure in the cylinder 8 is released, by countersprings 18 and 19. The

flow of motive fluid to and from the cylinder 8 is controlled in any suitable manner and one form of control will be hereinafter described. The construction of the pressing machine forms no part of this invention. 55 This invention relates to the work holder mechanism.

The work holder comprises a member, as a tape 21, movable from one side of the buck across the face thereof to the other side of the buck, means for moving the work holder from one side of the buck to the other side thereof and returning it when released to starting position, including a carrier movable from one side of the buck across the same and returnable independently of the work holder, and releasable means on the other side of the buck for coacting with the work holder and holding it from return movement with the carrier. The work holder 21 is here shown as movable from the rear side of the buck forwardly across the buck, transversely of the buck to the front side thereof, although obviously, it may be movable in any other direction relatively to the buck, the arcuate arm 25 carrying the head resilient tape, arranged and tensioned to spring upwardly away from the work on the buck when the press is opened and the releasable holding means is released. 80

22 designates the carrier, this being here shown as pivotally mounted at 23 to the frame of the machine below the table on which the bracket 3 is mounted and below the central part of the buck; that is, it is pivoted at a considerable distance below the face of the buck. The carrier comprises a radial arm 24 and an angular arcuate arm 25 at the end of the radial arm, the angular arm 25 extending upwardly from the radial arm 24 in position to move across the face of the buck 1 and it is normally arranged with its end at the rear of the buck 1. The tape 21 extends along the arms 24, 25 and preferably 85 these arms are tubular and the tape extends through said arms and is provided with a head 26 at its advance end which normally thrusts against the front end of the arm 25, or in other words, a shoulder 27 is provided 100

at the front end of the arm 25 against which the head 26 is normally held.

Means is provided for returning or holding the tape 21 with its head 26 against the shoulder 27 and this means is here shown as a reel 28 located in the case 29 carried by the arm 24 and on which the tape winds, the reel being actuated by a spring 30. The reel and its casing is located on the opposite side of the pivot 23 to that on which the major part of the radial arm 24 is located. The pivot 23 is a stud mounted in a laterally extending boss or hub 31 (Fig. 2) on the arm 24 and is fixed in a bearing formed in a bracket 32 projecting laterally from a leg of the frame 4. A segment 33 is mounted on said hub 31 to rotate therewith, this forming part of the motion transmitting means between the carrier 22 and the carrier for the releasable holding means to be presently described.

The carrier 22, in this embodiment of my invention, is power actuated as by a cylinder 34 having a piston 35 therein, the rod 36 of which is connected to a radial arm 37 on the hub 31, this radial arm being integral with the segment 33. The cylinder is pivotally mounted in a ball-and-socket joint at 38 in order to have an oscillating movement. The piston 35 is single acting and the carrier 22 is returned to its starting position when the pressure in the cylinder 34 is released by a returning spring 39.

The releasable holding means for holding the tape across the buck 1 after it has been carried across the buck by the carrier 22 is here illustrated as a latch 40 mounted on a movable carrier 41 which is connected to the carrier 22 by connections which permit movement of the carrier 41 upwardly in a position adjacent the forward edge of the buck when the carrier 22 is being actuated to move forwardly across the buck, and which permits the carrier 22 to return to its starting position independently of the carrier 41. The latch 40 is shown as pivoted at 42 to the carrier and as coacting with a jaw 43 rigid with the carrier. The latch has a pinch handle 44 arranged in juxtaposition to a handle 45 on the jaw 43. The latch coacts with the hook 46 provided on the head 26 of the tape 21. The carrier 41 has a hub 47 pivoted on a stud 48 which is mounted in a bearing 48a carried by the goose neck or bracket 3 under one end of the buck. It is normally located in the position shown in full lines, Fig. 1, and is movable into the dotted line position, Fig. 1, where the latch 40 is adjacent the front edge of the buck. As before stated the carrier 41 is actuated through connections between it and the carrier 22. These connections comprise a link 49 pivoted at one end at 50 to an arm 51 on the carrier 41 and having a pin 52 at its other end located in a slot 53 formed in the segment plate 33. This pin 52 and slot 53 constitute a lost motion

connection. The movement of the carrier 41 into its operative position is limited by an adjustable stop 54, here shown as a set screw threading through a stationary bracket 55 mounted on the stud 48 and coacting with the stop shoulder 56 on the carrier 41. The link 49 is composed of two sections, one telescoping within the other, the telescoping movement being resisted by a spring 57 which permits a yielding movement when the shoulder 56 engages the stop 54. The link 49 also includes a cushioning spring 58 for relieving the carrier 41 of shock when the carrier 22 returns to its starting position and the carrier 41 remains in its operated position. One section 49a of the link 49 is tubular and pivoted to the arm 51 of the carrier 41, and the other section 49b is a rod extending axially into the tubular section and provided with the pin or follower 52 working in the slot 53. The spring 57 encircles the rod 49b and thrusts against a head 49c on the rod and against a shoulder 49d at the lower end of the section 49a. The buffer spring 58 is located between the head 49c on the rod 49b and a head 49e in the upper end of the section 49a.

In operation, when motive fluid, as compressed air, is admitted to the cylinder 34, the carrier 22 moves upwardly, so that the arcuate arm 25 moves over the face of the buck 1 into the dotted line position, Fig. 1 and is spaced apart from the face of the buck, the arcuate arm 25 carrying the head 26 of the tape 21. During this movement of the carrier 22, the carrier 41 is moved upwardly by the link 49 and carries the latch 40 to its dotted line position, Fig. 1, where it receives the hook 46 of the head 26 of the tape 21 when the pressure in the cylinder 34 is released the carrier returns to its starting position without transmitting return motion to the carrier 41, this action being due to the lost motion connection provided by the pin 52 operating in the slot 53. During this return movement of the carrier 22 to starting position the tape 21 will unwind from the reel 28 and tension the spring 30. The press is then closed and when the pressing operation is completed, the press is opened and the latch 40 is released by pinching the handles 44 and 45 to release the hook 46 when the hook 46 is released the spring 30 of the reel 28 reacts and returns the tape 21 to its starting position. As the tape 21 is resilient it springs upwardly away from the buck and does not wipe over the work during its return movement. When the latch 40 is released the carrier 41 moves by gravity to its starting position.

The means for controlling the flow of motive fluid will now be described, although this means forms no part of this invention. The means for controlling the flow of air to the cylinder 8 comprises a valve casing 61 hav-

ing a normally closed spring pressed intake valve 62 and a normally open exhaust valve 63 therein which are connected by a stem 64 so that they act as a unit, and means for operating the valves. The intake end of the casting 61 is connected to a feed pipe 65 through a valve 66 and pipe 67, the function of this valve will be hereinafter set forth. The valve casing is connected from a point between the valves 62, 63 to the cylinder 8 through a pipe 68 which communicates with a coupling 69 opening into the intake port 70 at the upper end of the cylinder 8. The valves 62 and 63 are operated by a push button 71, the motion of which is transmitted through a lever 72 acting on an intermediate lever 73 which thrusts against a stem 74 of the exhaust valve 63. The movement of the push button 71 is against the action of a returning spring 75. Not considering for the time being the valve 66, upon depression of the push button 71, the intake valve 62 will be opened and the exhaust valve 63 closed so that air will pass from the feed line 65, through the valve casing 61 and pipe 68 to the cylinder 8 to actuate the piston 9 therein on its power stroke. These valves are locked in their operated position in order to hold the press closed, by a diaphragm 76 in a diaphragm chamber 77, the diaphragm acting upon a sliding stem 78 which thrusts against the intermediate lever 73. The pressure side of the diaphragm chamber 77 is connected by a pipe 79 to a coupling 80 on a pipe 81 which communicates with a casing 82 on the side of the cylinder, the casing 82 opening into the cylinder through a port 83. The port 83 is located in position so that it will be passed by the piston 9 when the piston approaches the end of its power stroke. When the port 83 is thus uncovered by the piston 9 air will pass from the cylinder 8 through the pipes 79 and 81 to the diaphragm chamber 77 to actuate the diaphragm 76 therein and hence lock the valves 62 and 63 in their operated position.

To open the press, the air is released from the diaphragm chamber 77 by opening a normally closed spring pressed exhaust valve 84 located in a valve casing 85 which is connected by pipes 86 to the pipe 79 or any pipe communicating with the pressure side of the diaphragm chamber 77. The exhaust valve 84 is operated by a trip lever 88 grouped with the push button 71.

In order to require both hands of the operator to be used in closing the press, a second push button 89 is employed which through levers 90 and 91 acts on the stem 92 of a normally open exhaust valve 93 located in a casing 94 which is connected by a pipe 95 to the coupling 69 at the intake end of the cylinder 8. The exhaust valve 93 is locked in its operated position by a diaphragm 96 in a

diaphragm chamber 97, the pressure side of which is connected by a pipe 98 to the coupling 80. The diaphragm 96 acts on a sliding stem 99 which thrusts against the intermediate lever 91.

Obviously, if only the button 71 is depressed, the air instead of passing to the cylinder, will pass out through the pipe 95 and exhaust valve casing 94; and if the push button 89 only is depressed no air at all will flow as the intake valve 62 will be closed. Hence, both push buttons must be depressed in order to obtain effective air flow to the cylinder 8 and must be held depressed until the piston 9 passes the port 83. The pressure side of the diaphragm chamber 97 is connected to the pipe 86 the outlet of which is controlled by the valve 84 operated by the trip lever 88 so that when the trip lever 88 is operated the air exhausts from both diaphragm chambers 77 and 97 and permits the valves in both casings 61 and 94 to return to their starting position.

The flow of air to the cylinder 34 which actuates the work holder carrier 22 is controlled by a valve casing 101 having a normally closed spring pressed intake valve 102 and a normally open exhaust valve 103 therein, which are connected by a stem 104 so that they operate as a unit. The intake end of the valve casing 101 is connected to the intake pipe 65 through pipe 105, valve 106 and pipe 107. The function of the valve 106 is to be hereinafter described. The valve casing 101 is connected from a point between the valves 102 and 103 by a pipe 108 to a coupling 109 communicating with the intake port 110 of the cylinder 34; the valves 102 and 103 are locked in their operated position by a diaphragm 111 in a diaphragm chamber 112 which is connected to the interior of the valve casing 101 by a duct 113a. The diaphragm 111 acts upon a sliding stem 114 which thrusts against an intermediate lever 115 corresponding to the levers 73 and 91. This lever is actuated by a push button 116 through the lever 117 which acts on the intermediate lever 115 against the action of a returning spring 118. The air is exhausted from the diaphragm chamber by a normally closed spring pressed release valve 119 in a valve casing 120 which is connected by a pipe 121 to a pipe 122 communicating with the pressure side of the diaphragm chamber 112. The valve 119 is operated by a trip lever 113. The air is also exhausted automatically from the diaphragm chamber 112 as will be presently described.

The valve construction forms no part of this invention. The valves 66 and 106 are for the purpose of preventing the operation of the work holder when the press is closed or for preventing the simultaneous operation of the work holder and the press head. This feature forms the subject matter of another application.

The valve 66 includes a casing 125 having a

diaphragm 126 therein, dividing it into two chambers 127 and 128, a valve 129 in the chamber 127 is normally held off its seat by a spring 130 and the chamber 127 below the valve is connected by a pipe 131 to the feed pipe 65. The chamber 127 also communicates with the pipe 67 and the chamber 128 is connected by a pipe 132 to the pipe 108 leading to the cylinder 34.

The valve 106 is of similar construction and has a diaphragm 133, lower and upper chambers 134 and 135, and a normally open spring pressed valve 136 in the chamber 134. Chamber 134 is connected below the valve 136 to the intake pipe 65 by the pipe 105 and the pipe 107 leads from the chamber 134 at a point on the other side of the valve 136 of the casing 101. Chamber 135 is connected by a pipe 138 to pipe 68 leading to the cylinder 8.

In operation, when the push buttons 71 and 89 are depressed to close the press head, that is, to admit air to the cylinder 8, the air flows from feed pipe 65, through pipe 131, through chamber 127 of valve 66, through pipe 67 as the valve 129 is held open by its spring 130, thence through valve casing 62, and pipe 68, to the cylinder 8 to actuate the piston therein. At the same time air flows from the pipe 68 through the pipe 138 to the upper chamber 135 of the valve 106 actuating the diaphragm 133 therein to close valve head 136 against its spring, so that if the push button 116 which controls the actuation of the work holder carrier 22 is depressed no air will pass to the valve casing 101 and cylinder 34, as the valve 136 is held closed. Likewise, if the buttons 71 and 89 are depressed while the carrier 22 is extended across the buck 1, no air will pass to the cylinder 8, as upon depression of the push button 116 air passes from the feed line 65, through pipe 105 to valve 106, the valve 136 being open, pipe 107, valve casing 101, and pipe 108 to the cylinder 34 and at the same time passes from pipe 108 through pipe 132 to the chamber 128 of the valve 66 to actuate the diaphragm 126 to hold the valve 129 closed.

Preferably, means is provided for automatically releasing the air from the cylinder 34 when the work holder carrier 22 has carried the head 26 of the tape 21 into engagement with the latch 40. As here illustrated, a normally closed spring pressed release valve 141 is located in a valve casing 142 carried by the frame. The casing 142 is connected by a pipe 143 and pipe 122 to the pressure side of the diaphragm chamber 112 which locks the valves controlling the flow of air to and from the cylinder 34 in their operated position. The release valve 141 is operated by a lever 144 having an engaging end 145 located in the path of a shoulder 146 (see Figure 1) on the radial arm 24 of the carrier 22, in position to be engaged as the carrier 22 approaches the limit of its stroke

or when it approaches its position occupied when the latch 40 engages the hook 46 at the end of the tape 21.

Upon depression of push button 116, obviously, air will be admitted to the cylinder 34 so that the carrier 22 is actuated to carry the tape across the buck until the hook 46 is engaged by the latch 40, at which time the shoulder 146 engages the trip lever 144 and operates the release valve 141 permitting air to exhaust from the diaphragm chamber 112, and the valves 102 and 103 to return to their starting position and hence the air to exhaust out of the cylinder 34 back through the pipe 108 and valve casing 101 past the exhaust valve 103. The release valve 119 provides for a quick exhaust of air from the cylinder 34 in the event the operator changes his mind about working the work holder before the work holder has traveled its full distance and carried the hook 46 into engagement with the latch 40. For instance, assuming that the operator starts the work holder in motion by depressing the push button 116 and then immediately changes his mind, he will then operate the trip lever 113 which is grouped with the push button 116, and thus will not wait until the carriers 22 and 41 complete their movement after which it would be necessary to release the tape 21 by operating the pinch handle 44.

Insofar as this invention is concerned, the pipe 108 may couple directly with the coupling 109 at the intake end of the cylinder 34 as shown in the diagrammatic view, Fig. 3. But in reality it is coupled to a valve casing 149, Figs. 1 and 2, which restrains a full or sudden flow of air to the cylinder to suddenly actuate the piston and the work holder, but permits a rapid exhaust of air from the cylinder. This check valve and its function forms no part of this invention and the valve is shown in application of Ernest Davis, 228,041, filed October 22, 1927.

What I claim is:

1. In a garment or laundry pressing machine in combination a frame; a buck mounted on the frame; a work holder movable across the buck; a movable carrier coupled with the work holder when said carrier is operated in one direction, to move the work holder across the buck; and releasable means to hold the work holder in position across the face of the buck during movement of the carrier back to starting position.

2. In a garment or laundry pressing machine in combination a frame; a buck mounted on the frame; a work holder normally arranged at one side of the buck and movable across the buck; a movable carrier coupled with the work holder when said carrier is operated in one direction, to move the work holder across the buck; releasable means to hold the work holder in position across the face of the buck during move-

ment of the carrier back to starting position; and means to return the work holder to starting position when released.

3. In a garment or laundry pressing machine in combination a frame; a buck mounted on the frame; a flexible and resilient work holder movable across the face of the buck from one side of the buck; a rigid carrier mounted for movement from a starting position below the level of the working face of the buck in an arc across and above the working face of the buck; means to couple the work holder and the movable carrier during such movement of the carrier across the buck; releasable means on the other side of the buck to receive the work holder during the return movement of the carrier back to starting position; a mounting for the releasable means below the level of the working face of the buck, all whereby the work holder is held off the face of the buck during forward movement of the carrier and pressed against the work on the buck during the return movement of the carrier.

25 4. In a garment or laundry pressing machine in combination a frame; a buck mounted on the frame; a flexible and resilient work holder movable across the face of the buck from one side of the buck and tensioned, when in operated position, to spring upwardly from the work when released; a rigid carrier mounted for movement from a starting position below the level of the working face of the buck in an arc across and above the working face of the buck; means to actuate the carrier; means to couple the work holder and the movable carrier during the movement of the carrier across the buck; releasable means on the other side of the buck to receive the work holder, and hold said work holder during the return movement of the carrier back to starting position; a mounting for the releasable means below the level of the working face of the buck, all whereby the work holder is held off the face of the buck during forward movement of the carrier and pressed against the work on the buck during the return movement of the carrier.

5. In a garment or laundry pressing machine in combination a frame; a buck mounted on the frame; a flexible and resilient work holder movable across the face of the buck; a rigid carrier mounted for movement from a starting position below the level of the working face of the buck in an arc across and above the working face of the buck; contact means between the work holder and the movable carrier by which the work holder is moved with the carrier during such movement of the carrier across the buck; releasable means on the other side of the buck to receive the work holder, and hold said work holder during the return movement of the carrier back to starting position, said releasable means being located below the level

of the working face of the buck, all whereby the work holder is pressed against the work on the buck during the return movement of the carrier.

6. In a pressing machine, a frame, a buck mounted on the frame, a work holder normally arranged at one side of the buck and comprising a flexible resilient tape having a head at its advance end, a carrier movable across the face of the buck and having a shoulder coacting with the head, means tending to pull the head against the shoulder, the carrier thrusting against said head to carry the tape across the buck and being returnable to its starting position independently of the tape, and releasable means for coacting with said head and holding the tape from return movement with the carrier.

7. In a pressing machine, a frame, a buck mounted on the frame, a work holder normally arranged at one side of the buck and comprising a flexible resilient tape having a head at its advance end, a carrier movable across the face of the buck and having a shoulder coacting with the head, means tending to pull the head against the shoulder, the carrier thrusting against said head to carry the tape across the buck, the carrier being returnable to its starting position independently of the tape, and releasable means for coacting with said head and holding the tape from return movement with the carrier, the carrier being tubular and the tape extending through the tubular carrier, and means acting on the tape to return the tape when released to its starting position in which the head is engaged with the shoulder on the carrier.

8. In a pressing machine, a frame, a buck mounted on the frame, a work holder comprising a tape movable across the face of the buck, a carrier pivoted to the frame below the buck and comprising a radial arm and an angular arm, the latter being movable across the face of the buck, the tape extending along said carrier and having a head at its advance end engaging the end of the angular arm, means acting on the tape tending to hold the head in engagement with the end of the angular arm and releasable means located on the opposite side of the buck to that on which the angular arm is located, for engaging the head and holding the tape from return movement with the carrier.

9. In a pressing machine, a frame, a buck mounted on the frame, a work holder comprising a tape member movable across the face of the buck, a tubular carrier pivoted to the frame below the buck and comprising a radial arm and an angular arm, the latter being movable across the face of the buck, the tape extending through the arms of the tubular carrier and having a head at its advance end engaging the end of the angular arm, means associated with the carrier tending to

pull the tape with its head against the end of the angular arm and releasable means located on the opposite side of the buck to that on which the angular arm is located for engaging the head and holding the tape from return movement with the carrier.

10. In a pressing machine, a frame, a buck mounted on the frame, a work holder normally arranged at one side of the buck, a carrier for moving the work holder from one side of the buck across the face of the buck to the other side thereof, said carrier being returnable to its starting position independently of the work holder, releasable means for holding the work holder in its position across the face of the buck during the return movement of the carrier, a second movable carrier for the releasable means and means connecting the carriers including a lost motion connection whereby the carriers move in unison into operative position but the first carrier is movable away from operative position without moving the second carrier.

25. 11. In a pressing machine, a frame, a buck mounted on the frame, a work holder normally arranged at one side of the buck, a carrier for moving the work holder from one side of the buck across the face of the buck to the other side thereof, said carrier being returnable to its starting position independently of the work holder, a releasable means for holding the work holder in its position across the face of the buck during the return movement of the carrier, a second movable carrier for the releasable means, and connections between the carriers whereby they move in unison from starting position.

40. 12. In a pressing machine, a frame, a buck mounted on the frame, a work holder normally arranged at one side of the buck, a carrier for moving the work holder from one side of the buck across the face of the buck to the other side thereof, said carrier being returnable to its starting position independently of the work holder, releasable means for holding the work holder in its position across the face of the buck during the return movement of the carrier, a second carrier for the releasable means, connections between the carriers whereby they move in unison from starting position, said connecting means comprising a lost motion connection permitting the first carrier to return to its starting position independently of the second carrier.

In testimony whereof, I have hereunto signed my name, at Syracuse, in the county of Onondaga, and State of New York, this 10th day of September, 1929.

EMIL A. WINNEWISSE.

CERTIFICATE OF CORRECTION.

Patent No. 1,835,254.

Granted December 8, 1931, to

EMIL A. WINNEWISER.

It is hereby certified that error appears in the printed specification of the above numbered patent requiring correction as follows: Page 1, line 76, after the word "buck" strike out the comma and words ", the arcuate arm 25 carrying the head" and insert instead a period and the words . The work holder is preferably a flat; and that the said Letters Patent should be read with this correction therein that the same may conform to the record of the case in the Patent Office.

Signed and sealed this 9th day of February, A. D. 1932.

(Seal)
